US0D1081911S

(12) **United States Design Patent** (10) Patent No.: **US D1,081,911 S**
(45) Date of Patent: ** Jul. 1, 2025

(54) **WATER PURIFIER**

(71) Applicant: **Coway Co., Ltd.**
Choongcheongnam-do (KR)

(72) Inventors: **Seul Gi Lee**, Seoul (KR); **Young Min Kim**, Seoul (KR)

(73) Assignee: **COWAY CO., LTD.**,
Choongcheongnam-Do (KR)

(**) Term: **15 Years**

(21) Appl. No.: **29/917,680**

(22) Filed: **Nov. 21, 2023**

(30) **Foreign Application Priority Data**

May 31, 2023 (KR) 30-2023-0020890

(57) **CLAIM**

The ornamental design for a water purifier, as shown and described.

DESCRIPTION

FIG. 1 is a front perspective view of a water purifier showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front perspective view of the water purifier with the cover removed.

1 Claim, 8 Drawing Sheets
